UNITED STATES PATENT OFFICE.

ROBERT FOSTER MERCER, OF BROOKLYN, NEW YORK, ASSIGNOR TO MERGENTHALER LINOTYPE COMPANY, A CORPORATION OF NEW YORK.

LINOTYPE LINE-CASTING MACHINE.

948,182, nat. to yah birds and Specification of Letters Patent. Patented Feb. 1, 1910.

Application filed June 9, 1908. Serial No. 501,094.

ARTICLE OF INVENTION.

To all whom it may concern:

Be it known that I, ROBERT F. MERCER, of Brooklyn, county of Kings, and State of New York, have invented a new and useful Improvement in Line-Casting Machines, of which the following is a specification.

My invention has reference to Mergenthaler machines, and kindred machines in which printing bars or linotypes having type on one edge are cast in a slotted mold against a composed line of matrices presented momentarily thereto.

The aim of the invention is to adapt a machine to produce blank slugs, leads etc., of a height less than that of the slugs bearing type faces, these low slugs to be used for leading or spacing purposes in making up a printing form. To this end I combine with an ordinary machine, such as represented in Letters Patent of the United States No. 436,532, or any similar machine having a slotted mold, a block or support adapted to be inserted in place of the usual line of matrices and provided in its face 25 with a tongue to enter and fill the front part of the mold slot, thereby reducing the depth of the slot, so that slugs or leads cast therein will be of reduced height, in order that there may be no danger of their receiving ink and 30 carrying the same to the paper.

In the drawings, Figure 1 represents a perspective view of my attachment. Fig. 2 is a vertical cross section through the casting mechanism of a Mergenthaler machine 35 with my device in use therein. Fig. 3 is an outline elevation showing the manner in which the device is seated between the usual matrix confining jaws.

Referring to the drawings, A represents 40 the usual slotted mold in which the slugs or linotypes are cast.

B is the vertical wheel in which the mold is mounted and by which it is carried from the casting to the ejecting position, and vice 45 versa.

C represents the perforated mouth of the melting pot by which the back of the mold is momentarily closed and through which molten metal is forcibly delivered to fill the 50 mold slot or cell a to form the slug, lead or linotype.

D is the vertically movable support for the matrix line commonly known as the first

elevator, and adapted to sustain the line of matrices directly against the front of the 55 mold during the ordinary casting operation.

E and F Fig. 3 are two horizontally movable jaws by which the matrix line is confined endwise in the casting position.

All of the foregoing parts are of the ordinary construction and are well known in the art.

Referring now to my improvement; G represents a metal block having externally the general form and size of a composed line 65 of matrices, so that it may be inserted like a line of matrices in the elevator D and between the jaws E and F. Blocks of this character, commonly known as quad blocks, are now in general use to support matrix 70 strips containing matrices for dashes, brackets, borders, etc. Instead of these inserted matrices I provide the block G with a projecting rib or tongue, g, which may be formed integral therewith or formed on a slide 75 seated in a dove-tail groove in a block, as shown. The face of the block is adapted to fit tightly against the face of the mold, and the tongue g is adapted to enter and tightly fill the front of the mold throughout its 80 length to a greater or less depth, according to the height of the slugs or leads to be produced. The effect of this rib when inserted in operative position as shown in Fig. 2, is to 85 reduce the depth of the mold slot a, so that the slugs or leads cast therein will be of a height less than that of the bodies of the slug on which type characters are formed.

By means of my attachment an ordinary linotype machine may be instantly adapted 90 to produce what are commercially known as low slugs or leads without characters thereon.

When the block is removed the machine is in a condition to be operated in the ordinary 95 manner for the production of type bars or linotypes.

Having described my invention, what I claim and desire to secure by Letters Patent, is—

1. In a linotype machine, the combination of casting devices comprising a longitudinally slotted mold constructed to produce type-high slugs, with a quad block provided with a projecting rib or tongue to close the 105 face of the mold and to project into and

partly fill it; whereby slugs or leads will be cast therein of a height less than the depth of the mold.

2. In a linotype machine, the combination of casting devices comprising a longitudinally slotted mold constructed to produce type-high slugs, with a quad block provided with a projecting rib or tongue detachably connected thereto to close the face of the mold and to project into and partly fill it;

whereby slugs or leads will be cast therein of a height less than the depth of the mold.

In testimony whereof I hereunto set my hand this third day of June, 1909, in the presence of two attesting witnesses.

ROBERT FOSTER MERCER.
